UNITED STATES PATENT OFFICE.

NELS JENSEN, OF GRASS VALLEY, CALIFORNIA.

DISPLAY RACK.

Application filed March 30, 1926. Serial No. 98,446.

This invention relates to display racks for bed springs and the primary object of the invention is to provide such a rack which will conveniently house a plurality of bed springs therein in the folded position and permit such springs to be readily withdrawn and placed in a demonstrating position.

My invention comprises a housing, preferably of portable open steel frame construction, having a plurality of vertically extending openings thereinto. A plurality of frames, each adapted to carry an exhibit bed spring thereon, are respectively pivotally mounted on a plurality of carriages slideable in the housing openings. In the folded position, the frames and springs are carried vertically on the carriages within the openings. When a spring is to be demonstrated, its carriage is withdrawn and the frame and spring pivotally moved to the horizontal position which the spring normally occupies in use. It is a further object of my invention to provide a display rack of this type.

In the accompanying drawing, I have illustrated one specific embodiment of my invention, but it will be understood that the invention can be otherwise embodied and that the drawing is not to be construed as defining or limiting the scope of the invention, the claims appended to the specification being relied upon for that purpose.

Figure 1 of the drawing illustrates a perspective view of one form of my invention.

Figure 2 is a detail view taken on line 35 11-II of Fig. 1.

The housing of my improved display rack, preferably made of structural steel as illustrated in the drawing, is also preferably made in portable sections, though it will of course be understood that the same can be a built-in construction, if desired. The housing illustrated comprises a plurality of vertically extending frame units, each constructed of vertically extending angle bars 40 1 and top and bottom connecting horizontal bars 2. These units are secured to the floor in relatively spaced relation by means of screws 3. In the drawing, I have shown only four of these units, although it will be understood that as many may be provided as desired. It will be seen that a vertically extending opening is provided between each two adjacent units and these openings are adapted to receive and house the bed springs 55 and their supporting frames in the folded

position. A protecting roof 4 is preferably provided over the top of the housing.

A carriage 5 comprising an inverted U-shaped channel bar mounted on rollers is provided for each opening and is adapted 60 to support the bed spring and its supporting frame therein. The front end of each carriage is supported on rollers 6 riding on the floor. The rear end thereof is carried by rollers 7 riding on tracks 8 formed of 65 channel bars secured to the lower ends of the frame units.

The bed spring 9 to be displayed is supported on a steel frame 10 and is secured thereto by wing nuts 11. This frame is 70 pivotally mounted at 12 to the upper ends of a pair of supporting angle irons 13 secured to the carriage. The frame is movable about these pivots to vertical and horizontal positions. In the vertical position, the frame and its spring are adapted to be moved with the carriage into its respective opening in the housing. In the horizontal position, the frame and spring occupy the normal position of the spring in use, the 75 outer end of the frame being supported by the well known folding legs 14. Springs 15 may be provided for counterbalancing the weight of the frame 10 when the same is being moved about its pivots 12.

It is believed that the construction and use of my invention will be obvious. Enough housing units are provided to make as many openings as there are springs to be demonstrated, each frame 10 being adapted to support one such spring. In the folded position, the springs are stored in a very neat and compact order. When a spring is to be demonstrated, the carriage supporting that spring is drawn out and the frame 80 dropped to the horizontal position illustrated, all of which will be understood. In this position, the spring is supported in the normal position which it occupies in use. Obviously, a mattress can be placed on the 85 spring if desired and the same demonstrated along with the spring.

While in the drawing I have shown a housing for only three springs, the same will preferably be installed in batteries 90 holding about ten springs. In such batteries, the spring supporting frames 10 will be mounted to pivot toward the center of the battery, that is, the right hand 5 frames will pivot to the left and the left hand 5 95 frames will pivot to the right.

to the right. In this manner the device can be mounted in a corner or against a wall without in any way interfering with the lowering of the frames.

5 Having thus described my invention, what I claim is:

1. A display rack for bed springs, comprising the combination of an upright housing having a plurality of vertically extending openings thereinto, a plurality of carriages mounted on rollers and respectively slidable into and out of such openings, each carriage comprising an inverted U-shaped channel bar, two upright supports carried by each carriage respectively adjacent the ends thereof, a frame for each carriage pivotally mounted on the said supports adjacent one end of the frame and adapted to support a bed spring thereon, the frames being movable about the pivots to a horizontal position when the carriages are withdrawn from the frame housing, and means at the free end of the frames for supporting the same in the horizontal position.
- 10 2. A display rack for bed springs, comprising the combination of an upright housing having a plurality of vertically extending openings thereinto, a pair of channel bars supported on the walls at opposite sides of each opening and extending horizontally thereinto adjacent the bottom of the openings, a plurality of carriages movable into and out of the openings, rollers supporting the inner end of each carriage
- 15 30 25 on the said channel bars, rollers supporting

the outer end of each carriage on the floor, two upright supports carried by each carriage, respectively, adjacent the ends thereof; a frame for each carriage pivotally mounted on the said supports adjacent one end of the frame and adapted to support a bed spring thereon, the frames being movable about the pivots to a horizontal position when the carriages are withdrawn from the frame housing, and means at the free end of the frames for supporting the same in the horizontal position.

3. A display rack for bed springs, comprising the combination of an open upright housing formed of steel angle bars, certain of the bars being spaced horizontally to provide a plurality of vertically extending openings into the housing, horizontally extending metal bars secured to the housing adjacent the bottom and at opposite sides of each opening, a plurality of carriages movable into and out of the openings, rollers supporting the inner end of each carriage on the last said bars, rollers supporting the outer end of each carriage on the floor, a frame for each carriage pivotally mounted on the carriage adjacent one end of the frame and adapted to support a bed spring thereon, the frames being movable about the pivots to a horizontal position when the carriages are withdrawn from the frame housing, and means at the free end of the frames for supporting the same in the horizontal position.

NELS JENSEN.
